CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

PRODUCTION OF ELECTRICAL ENERGY VARIATIONS.

Application filed October 20, 1920, Serial No. 418,263. Renewed December 2, 1926.

The present invention relates to an apparatus for producing energy variations in electrical circuits.

This invention is based upon a preceding invention disclosed by me in an application filed August 30, 1920, Serial No. 406,886. This application discloses the use of electrodes immersed in a gas and spaced in close proximity to normally prevent electric discharge through the gas even when subjected to a high potential gradient. This insulating property of the gap is secured by locating the active surfaces of the electrodes subjected to such a potential gradient a distance apart which is of the order of magnitude of the mean free path of the electrons, thus avoiding a sufficient number of collisions between electrons and atoms to initiate gaseous conduction.

20 A gap or tube of the above described character will conduct freely with a relatively small voltage drop between electrodes if a magnetic field of proper value is interposed between the electrodes. If the impressed voltage is increased to a certain critical or shut off value, however, the tube refuses to conduct and suddenly becomes insulating. By embodying the tube in a circuit including properly designed inductance and capacity together with means for generating a voltage higher than the voltage at which the tube will normally conduct, oscillatory currents may be generated, the frequency of which is determined primarily by the values of the inductance and capacity in the circuit. With this form of circuit arrangement, oscillations at substantially all desirable frequencies may be produced, the gap or tube serving to transform the energy derived from the source of potential into energy of oscillation.

35 An essential feature of the present invention then is the use of a tube of the character described which has the property of conducting current freely at a certain impressed voltage but which suddenly becomes insulating when the impressed voltage is increased to a critical value.

40 A further feature of the invention consists in the embodiment of a tube of the character described in an electrical circuit including inductance and capacity together with means for impressing upon the tube a volt-

age substantially greater than the voltage at which the tube will freely conduct. 55

It must be obvious to those skilled in the art that the present tube functions in a manner entirely different from any medium heretofore known or used for the production of oscillatory currents. Perhaps the most striking difference between the operation of the present construction and those previously known is the extreme rapidity and completeness with which it changes its state from conducting to insulating. In 65 this respect the present tube far surpasses any previously known electrical apparatus, and presents a new and efficient method of generating high frequency oscillations.

In the preferred embodiment of the invention the magnetic field strength is such as to cause the tube to normally conduct current freely in one direction and to insulate against the potential difference in the opposite direction. 70

In the accompanying drawings illustrating the preferred form of the invention Fig. 1 represents a section in elevation of one form of tube which may be employed in conjunction with an appropriate circuit for generating electrical oscillations, and Fig. 2 represents a typical oscillatory circuit with the tube embodied therein. 75

In the illustrated embodiment of the invention a tube of the character described in my copending application hereinbefore referred to is indicated at 10 and is provided with means indicated at 11 for creating a magnetic field of substantially constant strength in the region between the electrodes 90 where gaseous conduction takes place. This tube is embodied in a circuit 13 which includes a generator 14 capable of delivering about four-tenths of an ampere at 1500 volts. Also included in the circuit is a large inductance 16 in series with the tube and a relatively small capacity 18 shunted about the inductance. In addition to the inductance and capacity already described an additional capacity 20 is connected across 100 the circuit, as indicated, to provide a path for the flow of current when the tube shuts off upon reaching the critical voltage. The current from the generator is maintained substantially constant and high frequency 105 oscillations are prevented from flowing

through the generator by the use of choke coils 21 and 22 located on opposite sides of the circuit and operating in the usual manner. With this form of circuit, upon closing the switch 23 the current passing through the tube 10 increases in value and causes a rising voltage across the tube. The initial voltage at which current passes through the tube may approximate one to three hundred volts. This impressed voltage rises at a rate determined largely by the inductance 16 until the critical voltage is reached, at which the tube suddenly refuses to conduct further current and becomes insulating. Upon this sudden transformation of the tube from a conducting to an insulating state, the energy already stored up in the inductance 16 causes current to flow through the capacity 18, charging the latter to a high potential. The inductance 16 and capacity 18 together act as a resonant circuit which, when isolated from the remainder of the system by the insulating property of tube 10, is free to electrically oscillate in the usual manner, that is, the energy of the oscillating circuit is first stored up as electrostatic energy in the condenser and next as electromagnetic energy in the inductance. During the oscillation the potential difference across the inductance 16 undergoes a sinusoidal variation in amplitude and it will be seen that after a fraction of a cycle, the potential difference between the electrodes of tube 10, as determined by the voltage of the generator 14 and the voltage across the inductance 16, will be sufficiently low to again permit of gaseous conduction, and the cycle proceeds as before. The tube 10 therefore acts as an automatic feeding device, its purpose being to periodically feed energy into the resonant circuit 16, 18 and sustain the oscillations. The frequency of the oscillations is determined by the relative values of inductance 16 and capacity 18. These oscillations may be utilized in any suitable manner, as for example by a load circuit indicated at 26 which is inductively coupled with the circuit 13, as shown in Fig. 2.

With this type of circuit and a direct current generator delivering approximately four-tenths of an ampere at 1500 volts frequencies determined principally by the natural period of the circuit 16, 18 and ranging from 10 cycles to 100,000 cycles per second have been produced. The critical voltage at which the tube becomes insulating varies approximately as the square of the magnetic field strength applied to the tube and may accordingly be varied by suitable variations in the strength of this field.

The tube actually employed for the purpose of generating oscillations is constructed substantially as described in a copending application filed by me for a rectifier. This

tube consists of a sealed enclosing vessel 30 containing concentric cylindrical electrodes 31 and 32 constructed of non-magnetic material, such as molybdenum. Conduction takes place in the region separating the opposite surfaces of the two electrodes which are under a potential gradient and these surfaces are located in sufficiently close proximity to normally prevent gaseous conduction through the space separating them, even under excessively high potentials. A magnetic field with the lines of force extending substantially parallel to the axis of the electrodes may be created by a permanent magnet 34 located with respect to the tube, as shown in the drawings. The critical voltage at which the tube becomes insulating may be conveniently varied by adjusting the magnetic field. This adjustment of the magnetic field may be most readily carried out by moving the permanent magnet 34 toward or away from the receptacle 30. Cooperating with the permanent magnet are tubes or cylinders 37 and 38 of magnetic material which engage with opposite ends of the electrode cylinder 32. These cylinders are connected to the electrode 32 and to one another by a sleeve 39 of copper or similar non-magnetic material. It will be observed that the outer electrode 32 consists of a thin metallic cylinder having its opposite ends received in grooves formed in the adjacent faces of the cylinders 37 and 38. In order to permit the free escape of heat from the region surrounding the outer electrode 32, the connector sleeve 39 is preferably provided with openings or slots 44, as indicated in the drawings. The inner electrode 31 is connected at its opposite ends with iron rods 45 and 46, the rod 46 having a head 48 formed thereon and the rod 45 having its end threaded at 49. The electrode is preferably fused or welded to the rods to form a continuous rod having its central section of non-magnetic material, as indicated. Surrounding the outer ends of the rods 45 and 46 are insulating cylinders 50 and 51 of glass or similar material which are seated in recesses 52 formed respectively in the cylinders 37 and 38. The insulating cylinders may be held in place by collars 54 and 55 of copper or other non-magnetic material, each having a neck 56 which projects into the space between the rods and the surrounding insulator cylinders 50 and 51. The several elements are retained in assembled relation through the provision of a nut 58 engaging with the threaded end 49 and serving to draw the collars 54 and 55 against the ends of the cylinders 50 and 51. In order to insure that all paths through the supporting dielectric subjected to a potential gradient shall be long and that all paths through the gas shall be short, the outer ends of the cylinders 37 and 38 are

- counter-bored at 60 to separate the point of contact between the magnetic and insulating cylinders a substantial distance from the collars 54 and 55 which are in contact with the central electrode rod. In addition the collars are each provided with an annular flange 62 extending parallel but spaced away from the walls of the enclosing vessel. From an inspection of the drawings it will be observed that the outer cylinders do not contact directly with the enclosing vessel but are centered within the vessel and spaced away from the walls by spacing rings or washers 65. One of the leading-in wires 66 may be conveniently connected with the head 48, passing outwardly through the end of the tube and the other wire 67 may be connected with the sleeve 39, passing outwardly through the side of the tube at 68.
- It is preferred to employ helium as the medium within the tube through which gaseous conduction takes place, the small and light molecule of this gas resulting in certain distinct advantages. In the first place the small molecules of helium have a relatively long mean free path at any given pressure, making it practical to employ higher gas pressure than could be employed with a gas having larger molecules. Furthermore the light weight of the molecules enables the tube to change state from a conducting to an insulating medium and vice versa more rapidly than it could if a heavier gas were employed.
- The theory upon which this tube suddenly shuts off the flow of current when a critical voltage is reached is believed to be substantially as follows: By properly locating and positioning two electrodes within a gas filled receptacle, as described in my copending application, gaseous conduction between the surfaces of the electrodes is prevented, even when these electrodes are subjected to exceedingly high potentials. This is due to the fact that the distance separating the active surfaces of the electrodes is short and of the order of magnitude of the mean free path of the electrons. Owing to the short distance which the electrons travel, therefore, in passing from one electrode to the other, there is insufficient opportunity for collision between electrons and atoms to initiate electric discharge. When a magnetic field is interposed in the region between the electrodes, however, the path of travel of these electrons may be distorted sufficiently to cause collisions between electrons and atoms in sufficient numbers to initiate gaseous conduction, that is to produce substantial ionization. With a constant magnetic field, sufficient to render the tube conducting and with a small current passed therethrough, the tube will conduct. If the current passing through the tube be increased, however, the voltage rises, owing to the fact that the tube has a rising current voltage characteristic. This higher voltage tends to straighten out the curved paths of the electrons until a point is reached at which these paths again become so short as to prevent substantial ionization, thereby stopping gaseous conduction, and the tube suddenly becomes insulating and so remains until the applied voltage is lowered below the critical point.
- From the foregoing it will be evident that this oscillator is unique in that the characteristic curve (current abscissæ and potential ordinates) of the gaseous conduction device is discontinuous and that the current abruptly drops in response to a change in the ionization phenomenon accompanying the current flow without varying the magnetic field or other conditions of the gaseous discharge space except as affected by the current in said space and the potential across the space.
- I claim—
1. An electrical apparatus comprising a circuit including inductance and capacity and a generator of electrical potential, and means embodied in the circuit for conducting current at potentials less than the normal potential of the generator constructed and arranged to insulate against the conduction of current when a critical potential is reached less than the potential normally impressed by the generator but greater than the potential at which conduction initially takes place.
  2. An electrical apparatus comprising a circuit including inductance and capacity and a source of potential, two electrodes immersed in a gas and constructed and arranged to initially permit a flow of current therebetween when the circuit is closed and to insulate, in response to increase of the current against a further flow of current when a critical potential difference between the electrodes is reached less than the potential normally generated in the circuit.
  3. An electrical apparatus comprising a plurality of electrodes immersed in a gas and spaced in sufficiently close proximity to normally prevent gaseous conduction, a magnetic field interposed in the space between the electrodes to render the gap conducting at certain potentials, and means for impressing a potential upon the gap greater than that at which the gap will normally conduct to cause the gap to insulate at a certain critical voltage.
  4. An electrical apparatus comprising a plurality of electrodes immersed in a gas, a magnetic field interposed in the space between the electrodes of a value to render the gap conducting at certain potentials, and means for impressing a potential upon the gap greater than the potential at which the gap will normally conduct to cause the

- gap to insulate when a critical voltage is reached.
5. An electrical apparatus comprising two electrodes immersed in a gas and having their surfaces located in sufficiently close proximity to normally prevent gaseous conduction, means for creating a magnetic field in the region separating the electrodes sufficient to ordinarily cause gaseous conduction, and a circuit connected with the electrodes having inductance and capacity and including means for impressing upon the electrodes a potential greater than the potential at which the tube will conduct.
15. 6. An electrical apparatus comprising a circuit including two electrodes immersed in a gas and having their active surfaces located in close proximity to normally prevent gaseous conduction, means for interposing a constant magnetic field in the region between the electrodes to cause gaseous conduction below certain potentials, and means for impressing between the electrodes a potential difference greater than that at which the tube will conduct.
7. An electrical apparatus comprising a circuit having a source of constant potential and provided with inductance and capacity, electrodes immersed in a gas and having their active surfaces located in sufficiently close proximity to normally render gaseous ionization impossible, and a magnetic field interposed in the region separating the surfaces to normally cause gaseous conduction at potentials less than the potential normally generated in the circuit.
8. An electrical apparatus comprising two electrodes immersed in a gas and having their active surfaces separated a distance approximating the mean free path of the electrons, a magnetic field of substantially constant strength interposed in the region separating the surfaces, a circuit including the two electrodes and including a source of potential greater than that at which the tube will normally conduct, and an inductance and capacity included in the circuit and adapted to determine the period of oscillation of the circuit.
50. 9. An electrical system comprising a resonant circuit, a gaseous medium, means to cause the gaseous medium to freely conduct at voltages below a certain critical value and to suddenly change to an insulating state for voltages above the critical value, and means for impressing upon the gaseous region a rising voltage which starts at a value less than the critical voltage and increases to a value above the critical voltage.
60. 10. An electrical system comprising a resonant circuit, a gaseous medium having one dimension of the order of magnitude of the mean free path of electrons in the gas, means for lengthening the paths of electrons in the gas, and means for impressing a rising electric field in the small dimension of the gaseous region to cause the gaseous region to suddenly change from a conducting to an insulating state.
11. A system for generating electrical oscillations comprising a resonant circuit, two electrodes immersed in a gas and spaced apart a distance which is too short to normally permit of gaseous ionization, means for lengthening electron paths in the gas, and means for impressing a rising potential difference between the electrodes to allow the gaseous medium to feed energy into the resonant circuit for voltages below a critical value and to suddenly become insulating for all voltages above the critical value.
12. An electrical system comprising a circuit including inductance and capacity, a pair of electrodes immersed in a gas and spaced apart a distance which is too short to normally permit of gaseous ionization, means for causing the gaseous medium to become conducting at low voltages, and means for impressing an increasing potential difference between the electrodes to cause the gaseous medium to suddenly change to an insulating state above a critical potential difference.
13. An electrical system comprising a circuit including inductance and capacity, a gaseous medium having one dimension comparable in magnitude to the length of the mean free path of electrons in the gas and adapted to electrically conduct at low voltages, and means for impressing an increasing potential difference upon the gaseous region in a manner to cause electrons to traverse paths of decreasing length across the small dimension of the gaseous medium, whereby the gaseous medium is caused to change to an insulating state above a critical voltage.
14. An electrical oscillator comprising an oscillating circuit connected to a source of potential and a gaseous conducting device, and means producing a current voltage relation which changes abruptly in response to increase of current flow in the device, whereby the current abruptly drops when increased to a critical value.
15. An electrical oscillator comprising an oscillating circuit connected to a source of potential and a gaseous conducting device having means affording a characteristic curve which retrogresses abruptly at a critical point in response to increase of current therethrough.
16. An electrical oscillator comprising an oscillating circuit connected to a source of potential and a gaseous conducting device having means affording a substantially discontinuous characteristic curve so that the current substantially stops at a predetermined point of increase solely in response to increase of current.

17. An electrical oscillator comprising an oscillating circuit connected to a source of potential and a gaseous conduction device having spaced electrodes between which current may flow by gaseous ionization phenomena, characterized in that the spacing between the electrodes and the gas pressure are correlated to produce a gaseous discharge path in which the ionization phenomenon changes abruptly in response to increase of current, whereby the flow of current by gaseous ionization drops abruptly at a predetermined point of current increase. 5
18. An electrical oscillator comprising an oscillating circuit connected to a source of potential and a gaseous conduction device having spaced electrodes between which current may flow by gaseous ionization phenomena, characterized in that the space between the electrodes is restricted and conditioned to produce a gaseous discharge path in which the ionization phenomenon changes abruptly in response to increase of current, whereby the flow of current by gaseous ionization drops abruptly at a predetermined point of current increase. 10
19. An electrical oscillator comprising a gaseous conduction device having spaced electrodes between which current may flow by gaseous ionization phenomena, characterized in that the spacing between the electrodes and the gas pressure are correlated to produce a gaseous discharge path in which the ionization phenomenon changes abruptly in response to increase of current, whereby the flow of current by gaseous ionization drops abruptly at a predetermined point of current increase. 15
20. In an electrical oscillator comprising an oscillating circuit connected to a source of potential and a gaseous conduction device having spaced electrodes between which current may flow by gaseous ionization phenomena, the method of producing oscillations which comprises confining the current path through the gas to a restricted space and conditioning the space abruptly to become substantially non-conducting upon increase of current flow to a predetermined value in response to a change in the gaseous ionization phenomena accompanying the current flow. 20
21. In an electrical oscillator comprising an oscillating circuit connected to a source of potential and a gaseous conduction device having spaced electrodes between which current may flow by gaseous ionization phenomena, the method of producing oscillations which comprises confining the current path through the gas to a restricted space and conditioning the space abruptly to become substantially non-conducting upon increase of current flow to a predetermined value in response to a change in the gaseous ionization phenomena accompanying the current flow, while maintaining substantially constant the conditions of said space except as affected by the current in said space and the potential across the space. 25
22. An electrical oscillator comprising an oscillating circuit connected to a source of potential and a gaseous conduction device having means affording a characteristic curve which abruptly changes, toward zero current value, at a critical potential value, in response to increase of current therethrough. 30
20. In an electrical oscillator comprising
